UNITED STATES PATENT OFFICE.

LOUIS G. BAYER, OF HARTFORD, CONNECTICUT, ASSIGNOR TO PRATT & WHITNEY COMPANY, OF NEW YORK, N. Y., A CORPORATION OF NEW JERSEY.

YOKE FOR DIESINKING MACHINES.

Application filed October 8, 1920. Serial No. 415,557.

To all whom it may concern:

Be it known that I, LOUIS G. BAYER, a citizen of the United States, residing at Hartford, in the county of Hartford and 5 State of Connecticut, have invented certain new and useful Improvements in Yokes for Diesinking Machines, of which the following is a specification.

This invention relates to work supports 10 and particularly to a work-supporting member or yoke adapted to be secured to a block or piece of work to provide a supporting hold thereon. It is the primary object of the invention to provide such a member 15 which may be readily and easily secured to a piece of work and which will form a rigid and secure means thereon for engagement by a work-supporting crane. The more specific objects of the invention will become 20 apparent as the description proceeds.

Referring to the figures of the drawing:

Figure 1 is a front view of a die sinking machine showing the work support comprising the present invention in use thereon.

Fig. 2 is an enlarged perspective view of the work support.

Fig. 3 is a longitudinal section thereof taken on the line 3—3 of Fig. 2.

Fig. 4 is a cross section taken on the line 30 4—4 of Fig. 3.

The work support comprising the present invention is adapted particularly for use in the machine illustrated in my Patent No. 1,329,358, Feb. 3, 1920, although it will be understood that the invention is not necessarily so limited. In the structure illustrated I have provided two adjustable arms 35 adapted to engage a piece of work at opposite sides thereof. Means are provided for securing the arms in work-engaging position and other means are preferably provided for engaging the face of the work to secure the work support rigidly thereto. A further means, preferably comprising an integral projection on the body portion of the support, is provided for engagement by a supporting crane. It will be understood 45 that the structure shown is illustrative of the invention and may be modified within the scope of the appended claims.

Referring to the drawing by reference characters, 1 designates the frame of a milling machine having a work table 2 slidably mounted on a saddle 3 also slidably mounted 50 on a vertically adjustable knee 4. The work

W is mounted on the table and is adapted also to have the major portion of its weight supported by a pair of articulated arms 5 pivoted to the frame 1. A vertically adjustable rod 6 mounted in the end of each arm 60 5 forms an adjustable supporting connection between each arm and the work. The means, shown in detail in Fig. 2, by which each rod 6 is adapted to engage and support the work comprises the present invention 65 which will now be described.

The work support or yoke comprises in brief a body member 7 and a pair of relatively adjustable work-engaging arms 8. These arms are preferably arranged in an 70 overlapping relation and are adapted to be relatively adjusted longitudinally to permit the engagement of different sized pieces of work. Each arm is provided with a right angular extension 9 having a work-engaging 75 pin 10 in the end thereof. As a means for locking the arms in work-engaging position, I have illustrated each arm as provided with a plurality of transversely extending teeth 11 adapted to be engaged by a similarly 80 toothed member 12 held in the body member 7 by means of a pair of set screws 13 threaded into the body member and socketed into the member 12. A pin 14 mounted in the end of each arm 8 prevents the arm from 85 sliding out of the body member. I also provide supplemental work-engaging means 90 herein shown as set screws 15 on opposite sides of the arms 8. An integral projection 16 on the body member provides a means adapted to be directly engaged by the supporting rod 6.

Each work support is secured to its end of the work as follows. A pair of holes is drilled in opposite sides of the work to receive the pins 10. The set screws 13 are backed out to release the engagement of the members 12 with the teeth 11 of the arms 8, thus leaving the arms free to slide within the body member 7. The yoke is then 95 placed over the end of the work as shown in Fig. 1 and the extensions 9 are drawn tightly into engagement with the sides of the work, the pins 10 being fitted into the holes drilled into the work. The screws 13 100 are now tightened to engage the members 12 with the arms 8 to secure the arms against sliding movement. The screws 15 are also tightened to engage the work in 105 a manner to hold the yoke in the proper sup- 110

porting position on the work with the projection 16 substantially horizontal. In this position each yoke is secured rigidly to its end of the work and forms a rigid supporting hold for a lifting crane or the rod 6 as illustrated in Fig. 1.

What I claim is:

1. A work support comprising a body member, a pair of relatively adjustable arms 10 therein for engaging opposite sides of a work piece, means for securing the arms against relative movement in work-engaging position, supplemental means on the member for engaging the adjacent face of the work, and means on the member for receiving a work supporting element, the weight of the work being adapted to be supported by a plurality of the said supporting elements in supporting engagement with a plurality of the work supporting members.
2. A work support comprising a body member, a pair of relatively longitudinally adjustable overlapping work-engaging arms 25 therein for engaging opposite sides of a work piece, means for securing the arms against relative movement in the work-engaging position, supplemental means on the member for engaging the adjacent face of the work, and means on the member for receiving a work supporting element, the weight of the work being adapted to be supported by a plurality 30 of the said supporting elements in supporting engagement with a plurality of the work supporting members.
3. A work support comprising a body member, a pair of work-supporting arms 35 slidably therein, the arms being provided with substantially right angular extensions having work-engaging means thereon, means on the body member for engaging and securing the arms against sliding movement, and means on the member for receiving a work supporting element, the weight of the work being adapted to be supported by a plurality 40 of the said supporting elements in supporting engagement with a plurality of the work supporting members.
4. A work support comprising a body member, a pair of work-supporting arms 50 slidable therein, the arms being provided with substantially right angular extensions having work-engaging means thereon, means on the body member for engaging and securing the arms against sliding movement, supplemental means on the body member for engaging the adjacent face of the work, and means on the member for receiving a work supporting element, the weight of the work being adapted to be supported by a plurality 55 of the said supporting elements in supporting engagement with a plurality of the work supporting members.
5. A work support comprising a body member, a pair of work-supporting arms 60 slidable therein, the arms being provided with substantially right angular extensions having work-engaging means thereon, means on the member for receiving a work supporting element, the weight of the work being adapted to be supported by a plurality 65 of the said supporting elements in supporting engagement with a plurality of the work supporting members.

with substantially right angular extensions having work-engaging means thereon, means on the body member for engaging and securing the arms against sliding movement, supplemental means on the body member for engaging the adjacent face of the work, and means on the body member adapted to be engaged by a work-supporting crane.

6. A work support comprising a body member, a pair of relatively adjustable work 75 engaging arms therein, the arms being in engagement with each other in over-lapping relation and two corresponding faces of the arms being provided with transversely extending rack teeth, means in the member 80 provided with rack teeth corresponding to and facing the rack teeth on the arms, means for moving the last said means to engage the teeth thereof with the teeth on the arms, supplemental means on the member for engaging the adjacent face of the work, and means on the member for receiving a work supporting element, the weight of the work being adapted to be supported by a plurality 85 of the said supporting elements in supporting engagement with a plurality of the work supporting members.

7. A work support comprising a body member, a pair of work-supporting arms 95 slidably therein, the arms being provided with substantially right angular extensions having work-engaging means thereon and being also provided with transversely extending teeth, toothed means in the body member for engaging the toothed portion of 100 the arms to securely hold the arms against sliding movement, and set screws threaded into the body member and engaging the toothed means for binding the toothed means into engagement with the toothed portion of the arms.

8. A work support comprising a body member, a pair of work-supporting arms 110 slidable therein, the arms being provided with substantially right angular extensions 110 having work-engaging means thereon, means in the body member for engaging and securing the arms against sliding movement, and set screws threaded into the body member and adapted to engage the adjacent face of 115 the work.

9. A work support comprising a body member, a pair of work-supporting arms 120 slidable therein, the arms being provided with substantially right angular extensions having work-engaging means thereon, means in the body member for engaging and securing the arms against sliding movement, and set screws threaded into the body member and adapted to engage the adjacent face of 125 the work at opposite sides of the arms.

In testimony whereof, I hereto affix my signature,

LOUIS G. BAYER.
